S. L. WHITRIGHT,
FUEL VAPORIZING HEATER,
APPLICATION FILED SEPT. 26, 1919.

1,392,729.

Patented Oct. 4, 1921.

Inventor:
Samuel L. Whiting
By Albert C. Tammel,
Atty.

UNITED STATES PATENT OFFICE.

SAMUEL L. WHITRIGHT, OF NEW HAVEN, CONNECTICUT.

FUEL-VAPORIZING HEATER.

1,392,729.

Specification of Letters Patent.

Patented Oct. 4, 1921.

Application filed September 26, 1919. Serial No. 326,648.

To all whom it may concern:

Be it known that I, SAMUEL L. WHITRIGHT, a citizen of the United States, and a resident of New Haven, in the county of 5 New Haven and State of Connecticut, have invented certain new and useful Improvements in Fuel-Vaporizing Heaters, which improvements are fully set forth in the following specification.

10 This invention relates to improvements in constructions of that class available for heat-generating purposes and whereby is effected, in the practical operation of each thereof, the vaporization of the fuel, (preferably a hydrocarbon oil) fed thereto for consumption thereby, such constructions being well-designed fuel-vaporizing heaters.

The object of this invention is to provide a fuel-vaporizing heater which shall be simple and comparatively inexpensive as regards its construction; which shall embody novel features whereby is markedly facilitated the operation of cleaning the vaporization chamber and burner parts characteristic thereof and embodied therein; which shall be durable, efficient and reliable in practical service; and which shall possess certain well-defined advantages over prior analogous constructions.

20 The invention consists in the combinations, details and parts whereby, together with the novel disposition and relative arrangement of said parts, the attainment of the foregoing object is rendered practicable, 25 all of which will be hereinafter more specifically referred to and set forth in the several claims hereto appended.

The invention is clearly illustrated in the accompanying drawing, wherein:

30 Figure 1 is a plan view of a fuel-vaporizing heater embodying my said improvements, half of the burner dome being removed.

Fig. 2 is a view thereof partly in rear elevation and partly in central, vertical section, as along the dotted line $x-x$ of Fig. 1.

35 Fig. 3 is a view showing in perspective and detached a fragment of one of the radially-grooved members of the burner pile 50 made use of.

Fig. 4 is a view showing in perspective and detached one of the carbon arresters made use of.

40 Fig. 5 is a detail view showing in side elevation the supporting base and certain

minor burner parts more immediately cooperating therewith, the top portion of the near base-upright being broken away.

Having reference to the accompanying drawing, wherein similar reference-numerals denote like parts throughout the several views, I, in carrying out my present invention, make use of a burner-base 2, fitted with a central stack 2', and quite nearly surrounded marginally by a plurality of inter-communicating vaporizing segments 3, 3', 3'', 3''', each fitted with a straight vaporizing chamber, as 2''', wherein, by preference, is detachedly positioned an elongated carbon-arrester 2''; and each of the segments 60 65 aforesigned intersecting angularly the segment next in advance thereof, and generally in such relation thereto as to insure therefor an unobstructed open end, as 4, by way of which free access may be had to the 70 interior of the vaporizing chamber afforded thereby, as for the removal therefrom and replacement therein of its co-operating carbon-arrester, and which open end, of such vaporizing segment, is normally closed and 75 sealed by a suitable removable plug 4'.

Hence, it will be seen that the several intercommunicating vaporizing units of my improved heater, each, in the general series 80 85 thereof, angularly intersecting and communicating with, the unit next in advance thereof and having its individual open end, constitute a general, angular, marginal vaporizing chamber whose inlet is at 4'' and whose outlet is at 4'''. 90

Formed integral with, and immediately underlying the burner-base 2, is an elongated casing 5, angular in cross-section, and which forms a mixing chamber 5', whose air-intake is at 5'', (preferably duplicated 95 at the opposite end of the casing 5), and which mixing chamber is in unobstructed, direct communication with the stack 2'.

At the intake of the general vaporizing chamber aforesigned I purpose making use 100 of a depending intake nozzle 5''', to which may be attached, in the usual manner, a supply pipe 6, duly controlled and leading from any appropriate general supply, (not shown), of a hydro-carbon fuel, as kerosene, preferably under pressure, all as in common practice; while at the outlet of said general vaporizing chamber I purpose using a depending delivery nozzle 6', in communication with a suitable upstanding delivery tip 6'', 110

through the medium of a suitable feed-pipe, here denoted as a whole by the reference-numeral 6", and preferably composed of suitable intercommunicating pipe-sections 5 and unions, substantially as illustrated in Fig. 2, a suitable needle-valve, as 7, being provided, whereby the delivery orifice, as 7', may be readily freed from any products of vaporization which may, in practice, accumulate thereat, and otherwise tend to clog 10 said delivery orifice.

7" is a tubular chimney housing at its lower end-portion the tip 6", extending therefrom upwardly and somewhat into the 15 mixing chamber 5', shiftable longitudinally, that is, adjustable upwardly away from the tip 6" and downwardly to a seating engagement therewith, and by way of which the fuel vaporized in the general vaporizing 20 chamber of my improved heater, in the practical operation thereof, and conducted from such general vaporizing chamber through the medium of the feed-pipe 6" to said tip for delivery thereat, finds its way into the 25 interior of said mixing chamber, where it becomes duly mixed with atmospheric air, in-rushing by way of the intake 5", the resulting mixture duly moving from thence upwardly by way of the stack 2' to and into 30 the interior of the burner proper of the device, the latter embodying, conjunctively with its base 2, a plurality of plate-like members, 8, 8', 8", 8", superimposed one upon another and one of the faces of each thereof 35 having formed therein a multiplicity of radial, ignition grooves, 7", said superimposed members constituting a vapor-distributing burner-pile whose ignition grooves permit the escape, in jet-like volumes, of the 40 vaporized fuel from the interior of the burner proper in substantially all lateral directions relative thereto and as determined by said grooves.

More specifically each of said burner-pile 45 members comprises an uninterrupted marginal portion inwardly from which, at suitable points therealong, project a plurality of stack-engaging arms 9, 9', 9", 9", whose free ends, preferably enlarged as shown, lie 50 in close juxtaposition to said stack, at the corresponding, flattened walls thereof, and whereby each burner-pile member, while being freely displaceable upwardly relative to the stack aforesaid, is held by such stack 55 through the coöperation therewith of the stack-engaging arms aforesaid, against casual horizontal displacement relative to its immediate neighbor or neighbors.

Further, the marginal portion of each of 60 the burner-pile members exceeds somewhat in depth the depth of each of the stack-engaging arms associated therewith, whereby, as will be readily understood, is facilitated the distribution and formation of the ignition 65 grooves contemplated therefor.

There is detachedly seated on the burner-pile aforesaid a burner-dome 10, held against displacement, save upwardly, through the medium of its depending peripheral lip 10', which latter embraces a substantial portion of the topmost member of said burner-pile, substantially as shown; and a greater or less number of said burner-pile members being availed of, as may be found expedient in 75 practice.

The cut-out portions of each of the burner-pile members form, as it were, a plurality of minor chambers within the burner-pile all in intercommunication by reason of the clearance afforded through the variation in depth 80 of the marginal portion of each burner-pile member and the stack-engaging arms associated therewith, said chambers being in direct communication with the interior of the dome 10 and the latter in direct communication with the stack 2', as will be clearly 85 apparent.

For displaceably sustaining the burner proper, including the casing forming the air-mixing chamber thereunder, I provide a 90 general base 10", mainly depressed as shown, to receive and contain a priming charge of fuel, and having formed integral therewith, by preference, a pair of uprights 10", 10", each of which has an angular notch 11, at 95 its upper extremity, for the reception, detachably, of the angular casing aforesaid, whereby the burner proper, while being duly held in its upright position for service, may, conjunctively with the casing aforesaid, and other parts associated therewith, be lifted relatively to the uprights aforesaid and accordingly displaced from the general base provided for coöperation therewith.

It is contemplated that each of the carbon 105 arresters made use of shall comprise a section of wire of suitable length, duly jacketed with asbestos fiber or other suitable material, substantially as shown.

In operation a priming charge of kerosene, or other fuel, is first poured into the depression of the general base, and there ignited for the purpose of primarily heating the burner structure, as a whole; whereupon the hydro-carbon fuel, in fluid form, is conveyed, preferably under air-pressure, to and into the general vaporizing chamber, where it is duly vaporized, the resulting vapor being from thence delivered, by way of the feed-pipe 6", tip 6" and chimney 7", to and 110 into the mixing chamber 5', where it is duly mixed automatically with air of a suitable volume, which fuel-mixture is thereupon 115 automatically conducted to and into the interior of the burner proper, including its dome 10, by way of the stack 2, said mixture thereupon escaping in jet-like volumes by 120 way of the ignition grooves of the burner-pile, and laterally therefrom at a multiplicity of points as determined by said 130

grooves, the vapor-mixture being ignited by the user as it thus escapes from the burner-pile; and thereafter the operation of feeding the fuel in a fluid state to and into the 5 general vaporizing chamber, vaporizing such fuel, duly mixing therewith a proper volume of air, and consuming the resultant mixture by combustion as it escapes as explained from the burner-pile, continues automatically so long as the supply of fuel for consumption as explained is maintained, as will be clearly understood.

The interior of each segment of the general vaporizing chamber may be cleansed of 15 products of vaporization by dislodging the plug normally closing the otherwise open end of any unit of such chamber and thereafter duly manipulating and withdrawing the carbon arrester positioned therein, such ar- 20 rester, upon being subjected to a cleansing process, being replaced within such unit, or a fresh one being substituted therefor,—the dislodged plug being also replaced.

The operation of the needle valve needs 25 no description, the same being quite common in the art; but it may be here pointed out that a carbon arrester, such as herein contemplated, may, when deemed advisable, be used within the horizontal section of the 30 feed-pipe 6", such feed-pipe section having an open end normally closed by a suitable plug, as 11', similar in all essential details to the plug closing the open end of any of the vaporizing segments aforesaid.

35 In cleansing the interior of the burner proper, it is only necessary to lift the dome 10 from its seat on the top-most burner-pile member; then displace, by lifting, the several burner-plate members, cleanse them, replace them, and then replace the burner dome,—an operation easily accomplished and one that markedly facilitates the cleansing of the interior of the burner.

It will be seen that my improved heater 45 is well adapted for the purposes for which it is designed or intended, and that the same may be modified to a considerable extent without departure from the spirit and principle of my invention as coming within 50 the scope of the claims hereto appended.

I claim:

1. A fuel-vaporizing heater comprising a burner fitted with a base mainly surrounded marginally by a general vaporizing cham- 55 ber composed of a plurality of straight an-

gularly-intersecting, open-ended units constituting a general vaporizing chamber, and having a casing formed integral therewith and depending therefrom, the interior of said casing constituting a mixing chamber; 60 plugs removably closing the open ends of said units; a general base detachedly supporting said burner; a supply pipe for conducting fuel in a fluid state to and into the general vaporizing chamber aforesaid; a feed- 65 pipe for conducting the vaporized fuel from the interior of said general vaporizing chamber to and for delivery at a point beneath the casing aforesaid, by way of a suitable delivery tip thereat; and a vertically adjust- 70 able chimney, the latter establishing communication between said tip and said mixing chamber.

2. A heater comprising a burner fitted with a base having a central stack formed 75 integral therewith; a fuel-distributing pile, detachedly positioned on said base and held against displacement in all radial directions from, and through the medium of said stack; and a dome, the latter detachedly positioned 80 on said pile, and held thereby against displacement in all radial directions therefrom.

3. A heater comprising a burner fitted with a base having a central stack; a fuel-distributing pile positioned on said base, said 85 pile embodying a plurality of superimposed radially-grooved members held, each through the medium of said stack, against horizontal displacement relative to its neighbor or neighbors, said grooves permitting the es- 90 capse of vaporized fuel from the interior of said pile in substantially all lateral directions relative thereto; and a dome, the latter detachedly seated on said pile,

4. A heater comprising a burner fitted 95 with a base; a plurality of plate-like mem- bers superimposed one upon another, and col- lectively detachedly positioned on said base, each of said members provided with a mul- tlicity of radial ignition grooves at one face 100 thereof; and a dome, the latter detachedly seated on the topmost member of said super- imposed members and thereby held against horizontal displacement; said base affording a central stack whereby said superimposed 105 members are held, against horizontal dis- placement, each relative to its neighbor or neighbors.

SAMUEL L. WHITRIGHT.
